UNITED STATES PATENT OFFICE.

THOMAS YATES, OF DUBUQUE, IOWA.

IMPROVEMENT IN CORN-HARVESTERS.

Specification forming part of Letters Patent No. 60,318, dated December 4, 1866.

To all whom it may concern:

Be it known that I, THOMAS YATES, of Dubuque, in the county of Dubuque and State of Iowa, have invented a new and Improved Machine for Harvesting and Husking Maize or Indian Corn; and I do hereby declare that the following is a full, clear, and exact description thereof, which will enable others skilled in the art to make and use the same, reference being had to the accompanying drawings, forming part of this specification, in which—

Figure 1 is a plan or top view of my invention; Fig. 2, an inverted plan of the same; Fig. 3, a transverse vertical section of the same, taken in the line $x x$, Fig. 2; Fig. 4, a vertical section of a portion of the same, taken in the line $y y$, Fig. 1.

Similar letters of reference indicate like parts.

This invention relates to a new and improved machine for harvesting and husking maize or Indian corn; and it consists in a cutting device, constructed, arranged, and applied to a wagon in such a manner as to cut the ears of corn from the standing stalks, and at the same time sever the lower ends of the husks from the butts of the ears, and strip the severed husks from the same. The invention also consists in a novel construction of the wagon for the quick turning or guiding of the same in the prosecution of its work.

A represents the body of a wagon, mounted on four wheels, both axles B B' of which are attached to the body by king-bolts $a a'$. The front axle B is provided with what may be termed a "double draft-pole," or one composed of two parts, $b b$, connected at their front ends by an upright bow-shaped bar, c . Considerable space is allowed between the two parts $b b$ of the draft-pole, and the horses are at the outer sides of said parts, the traces of the harnesses being connected to the wagon by the usual whiffletrees $d d$. The front wheels of the wagon are secured to the front axle B, so that said axle will turn with the wheels, and on the center of axle B there is fitted loosely a sleeve or collar, e^* , to which the king-bolt a is attached, said bolt passing through the front part of the bed of the wagon. There are also, on the axles B, two

cams, $e e$, one at each side of the king-bolt, said cams being between the inner ends of the two parts $b b$ of the draft-pole, through which the axle B passes loosely. At the front end of the wagon-bed there are fingers f , which are stationary or fixed, parallel with each other, and pointed at their front ends. Directly underneath these fingers there is a cutter, C , composed of a series of parallel knives, g , which slide underneath the fingers f , and are operated from the cams $e e$, pins h projecting from the cutter-plate into the cams $e e$.

As the machine is drawn along, the horses walk in the spaces between the rows of corn, a row being between the horses and the two parts $b b$ of the draft-pole, the curved or bow-shaped bar c , which connects the front ends of said parts passing over the stalks without breaking them down. The stalks are caught by the fingers f , and under the draft or forward movement of the machine are slightly bent forward, and the ears are brought down to the fingers f and severed at the butts, and the husks also severed. The ears fall or pass into the body of the wagon, while the husks readily drop off from the ears, and the cut stalks fall in front of the wagon on the ground.

The back axle B' is held in position or prevented from turning by means of a forked bar, D , attached to it, said bar, when raised to a vertical position, engaging with catches $i i$ at the ends of a bar, E , secured transversely in the rear part of the body of the wagon, and through which bar the king-bolt a' of the rear axle passes. The forked bar D , when engaged with the bar E , holds the axle B', preventing it from turning, and at any time when it is necessary to turn the wagon quickly or suddenly the forked bar D is shoved down, and thereby disengaged from the bar E , which allows the rear axle to turn by the driver moving bar D either to the right or left, as may be required.

Having thus described my invention, I claim as new and desire to secure by Letters Patent—

1. The fixed or stationary fingers f , at the front part of the bed of a wagon, and having a reciprocating cutter, composed of a se-

ries of knives, *g*, working underneath it, in combination with the double draft-pole, composed of two parts, *b b*, connected by a bow-shaped bar, *c*, at their front ends, substantially as and for the purpose specified.

2. The pivoted or turning rear axle *B'*, with forked bar *D* attached, in connection with the

catches *i i* on the bar *E*, substantially as and for the purpose specified.

THOMAS YATES.
